US0D1086247S

(12) **United States Design Patent** (10) **Patent No.:** **US D1,086,247 S**
(45) **Date of Patent:** **** Jul. 29, 2025**

(54) **WELDING MACHINE**

(71) Applicant: **Panasonic Intellectual Property Management Co., Ltd.**, Osaka (JP)

(72) Inventors: **Bo Yu**, Osaka fu (JP); **Hideki Ihara**, Hyogo ken (JP); **Kota Horie**, Osaka fu (JP)

(73) Assignee: **PANASONIC INTELLECTUAL PROPERTY MANAGEMENT CO., LTD.**, Osaka (JP)

(**) Term: **15 Years**

(21) Appl. No.: **29/827,752**

(22) Filed: **Feb. 22, 2022**

(30) **Foreign Application Priority Data**

Oct. 18, 2021 (JP) ..... 2021-022624 D

(57) **CLAIM**

The ornamental design for a welding machine, as shown and described.

DESCRIPTION

FIG. 1 is a front, top, and right side perspective view of a welding machine, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged partial front elevational view thereof, appearing in the section marked by boundaries marked **8** in FIGS. 2 and 4.

The broken lines in the drawings illustrate portions of the welding machine which form no part of the claimed design.

1 Claim, 8 Drawing Sheets
